HENRY HASSENPLUG, OF HUNTINGDON, PENNSYLVANIA, ASSIGNOR TO
HIMSELF AND EDWARD HASSENPLUG

Letters Patent No. 65,669, dated June 11, 1867.

IMPROVEMENT IN SAWING MACHINES.

The Schedule referred to in these Letters Patent and making part of the same.

TO ALL WHOM IT MAY CONCERN:

Be it known that I, HENRY HASSENPLUG, of Huntingdon, in the county of Huntingdon, and State of Pennsylvania, have invented a new and improved Combined Sawing and Mortising Machine; and I do hereby declare that the following is a full, clear, and exact description thereof, which will enable others skilled in the art to make and use the same, reference being had to the accompanying drawings, forming part of this specification, in which—

Figure 1 represents a side elevation, partly in section, of my combined sawing and mortising machine.

Figure 2 is a plan or top view, partly in section, of the same.

Figure 3 is a longitudinal sectional elevation of the same, the plane of section being indicated by the line *x x*, fig. 2.

Figure 4 is a transverse sectional elevation of the same, the plane of section being indicated by the line *y y*, fig. 1.

Figure 5 is a detail view, to be hereinafter referred to.

Similar letters of reference indicate like parts.

This invention relates to a machine on which a circular saw, a reciprocating saw, and a chisel can be arranged in such a manner that all work which can be performed by the said instruments can be done on the machine by hand or other power. The invention consists in the mode of applying and regulating the power by which the machine is driven, so that the latter may be used for light and heavy work, as may be desired. The invention also consists in an automatic feed-motion, in the manner of securing and adjusting the bed for mortising, and finally, in the device for holding the reciprocating saw, wherein the chisel for mortising may also be secured.

A represents an oblong frame, made of wood or other suitable material, and supported upon pillars B, as shown in the drawings. C is a transverse horizontal shaft, mounted in suitable bearings in the frame A, and provided at one end with a pinion, *a*, and crank *b*, as is clearly shown in figs. 1 and 2. D is another transverse shaft arranged on the frame A, and provided at one end with a toothed wheel, *c*, which meshes into the pinion *a*, as shown. A crank, *d*, is also attached to the end of the shaft D. A circular saw, E, is mounted on the shaft C, and when the same is to be used a stationary bed is arranged on the top of the frame A, and the machine is fed by hand or by suitable machinery as now in use in machine sawing. Between two slotted uprights, F F, which are stationary, arranged at the sides of the frame A, is held the vertical reciprocating saw-frame G, to which motion is imparted by connecting-rods *e e*, their upper ends being pivoted to pins *f f*, projecting from the side of the saw-frame, and their lower ends secured eccentrically to a transverse shaft, H, on which a pinion, *g*, is mounted that meshes into the cog-wheel *c* on shaft D. Thus, as either the shaft C or D is revolved, motion is imparted to the shaft H and to the said frame G, the latter moving up and down, guided by the slotted uprights F. By applying power to the shaft C a slow motion is given to the saw-frame, while, when quick motion is required, the power is applied directly to the shaft D. The uprights F F are connected on top by a cross-bar, *h*, on which bearings are arranged for an oscillating shaft, *i*. The caps on these bearings are hinged or otherwise attached, so that the shaft *i* can be easily removed if desired. An arm, *j*, projects at right angles from the outer end of the shaft *i*, and is firmly secured to the latter. The arm *j* is connected by a rod, K, to the end of a fly-lever, L, secured to one end of the shaft C, as shown. The lever L is slotted, and the rod K is attached to it by a pin passing through the slot and held in place by a nut, whereby the distance of the lower end of the rod K from the centre of the shaft C can be regulated. To the inner end of the shaft *i* is secured at right-angles an arm, *l*, the end of which is connected by a rod, *m*, with a plate, *n*, which is secured to a cross-bar, *o*, of the saw-frame G. By revolving the shaft C the shaft *i* is oscillated, and by its connections *m* and *n* with the saw-frame the latter is moved up and down. If desired, the gear-wheels *a*, *c*, and *g*, and the system of levers above described, may be employed at the same time for moving the saw-frame up and down, or either of them alone. To use the gear-wheels alone, the shaft *i* can be taken off, on account of the open bearings. To use the lever motion alone it will be necessary to move the shaft H in its bearings, so as to throw the pinion *g* out of gear, thereby rendering it necessary to move the rods *e e* on the pins *f f*, and to secure them so that the rods *e*

will be vertical on the shaft H. The upper ends of the rods e are secured by small keys or screws to the pins f, which are provided with two holes each, to receive the keys or screws, so as to allow for the shifting of the rods e. The shaft H is shown out of gear in fig. 4. When the pinion g is in gear, the shaft H is prevented from shifting of its own accord by a pivoted clamp p, (shown in fig. 1,) or by some other stop, arranged on the side of the upright F, opposite to that on which the pinion g is arranged. The rod K is provided with a handle, q, whereby one hand of the operator may be used to pull directly on the said rod while the other turns the crank on the shaft D. This handle q, as well as the fly-lever I, serves greatly to increase the power of the driving mechanism. The lever I has been found to do better service than a fly-wheel, especially when its free end, i. e., that to which the rod K is not attached, is arranged so as to swing downwards when the saw-frame descends. The saw-frame consists of two cross-bars on which slotted arms, K, may be arranged, to the front end of which the saw L is attached, as shown in fig. 1. Said slotted arms are so arranged that the saw can be set at a greater or less distance from the saw-frame. They have been fully described in the Letters Patent granted to me on the eighteenth day of December, 1866. The saw L may also be secured directly between the cross-bars of the saw-frame, as is indicated by red lines in figs. 3 and 4. In that case its upper end is inserted in a slot provided in the under surface of a block, r, which is secured to the upper cross-bar of the saw-frame, as shown, and is held in place by a pin, s, as shown more particularly in fig. 5, which is an inverted view of the block r. The slot in the latter for holding the saw is widened in the centre, so as to form a hole, in which the mortising chisel M (the operations of which will be hereafter described) is inserted, and is also held by the pin s. When the reciprocating saw L is used, a slotted carriage, N, is placed upon the frame A, being provided with rollers t at its under side, as shown, so as to slide easily backwards and forward on the frame A, the saw L passing through the slot. A ratchet-bar, w, is secured to the carriage, as shown in figs. 1, 2, and 4. A curved arm or lever, O, is hinged to a crank on the oscillating shaft i, which is so arranged that its forward curved part is heavier than its lower end, so that the latter will be elevated above the carriage N, as shown by red lines in fig. 1. A weight, v, can be secured by means of screws to the lower end of the lever O, and then the same will be held down upon the ratchet-bar w, as shown. By the motion of the shaft i the lower end of the lever O is moved back and forth, and while moving back it carries the carriage N along, and thus feeds the wood that may be placed thereon to the saw. When no feed is required the weight v is removed, and then the lever O will not come in contact with the ratchet. Thus the reciprocating saw can be used with or without an automatic feed, can be made to work with more or less power by the use of the gear-wheels and lever arrangements, and with more or less speed, and can be removed altogether, so that the circular saw or the chisel may be used, as may be desired. When mortising is to be done, the saw L is removed and the chisel M is secured in the block r and held in place by the pin s in the manner above described, and as shown in figs. 3, 4, and 5. The carriage N is removed from the frame A, and the weight v is removed from the end of the lever O. A bed, P, consisting of a wooden plate provided with slotted supports Q, is placed below the chisel, the supports resting upon the wedge-shaped block R in such a manner that by moving the said block forward or backward the bed P can be raised or lowered, and as it is provided with pins at its ends which fit around the sides of the uprights F, the said bed will always retain its proper position, no matter how much it may be raised or lowered. A pin, w, is inserted in one of a series of holes, which are provided in the block R, so as to come in contact with that edge of the support Q which reaches to the lower part of the block, thus preventing the block R from sliding out from under the supports Q, which, and the bed P, are firmly secured in position by a bolt, S, passing through the slot in the supports, and through a cross-bar, T, arranged between the uprights F, as clearly shown in fig. 3. The head of the bolt S, and the nut z by which the bolt is held secure, prevent longitudinal motion of the bed P. The uprights F, between which the latter securely fits, prevent lateral motion of the same, while the bolt S prevents vertical motion. By loosening the nut z and removing the pin w, the bed P can be raised or lowered by adjusting the wedge-shaped block, and the bed is then again secured in position by reinserting the pin w and tightening the nut z. The chisel can now be operated by the same mechanism by which the reciprocating saw is moved, and any suitable sort of mortises may thus be formed on this machine.

What I claim as new, and desire to secure by Letters Patent, is—

The arrangement of the lever m, plate n, shaft i, levers j, k, and I, by which motion is imparted from the shaft C to the reciprocating frame G, as herein set forth, for the purpose specified.

HENRY HASSENPLUG.
